Care and User Guide for Infinity Drain's Linear Drains, frame 0:06:0:49, announced in YouTube on Sep. 29, 2022[online], [site visited Feb. 18, 2023], Available from the internet URL: <https://www.youtube.com/watch?v=B9OwQhdkgzg&list=PL3VDSgoGQUi31v5ORBG2xeIgBqw2rkWv&index=1> (Year: 2022).*

Primary Examiner — Amy C Wierenga*Assistant Examiner* — Kathryn Elizabeth Zieno(74) *Attorney, Agent, or Firm* — F. Chau & Associates, LLC(57) **CLAIM**

The ornamental design for a hair strainer, as shown and described.

DESCRIPTION

FIG. 1 is a top perspective view of a hair strainer in accordance with the present invention;

FIG. 2 is a bottom perspective view thereof;

FIG. 3 is a first side view thereof, the opposing side being a mirror image;

FIG. 4 is a top plan view thereof;

FIG. 5 is a second side view thereof, the opposing side being a mirror image; and,

FIG. 6 is a bottom plan view thereof.

The broken lines shown in the drawings illustrate portions of the hair strainer that form no part of the claimed design.

1 Claim, 3 Drawing Sheets
